UNITED STATES PATENT OFFICE.

PAUL MACGAHAN, OF PITTSBURGH, PENNSYLVANIA, ASSIGNOR TO WESTINGHOUSE ELECTRIC & MANUFACTURING COMPANY, A CORPORATION OF PENNSYLVANIA.

CASING STRUCTURE.

Application filed January 30, 1923. Serial No. 615,865.

To all whom it may concern:

Be it known that I, PAUL MACGAHAN, a citizen of the United States, and a resident of Pittsburgh, in the county of Allegheny and State of Pennsylvania, have invented a new and useful Improvement in Casing Structures, of which the following is a specification.

My invention relates to casing structures and particularly to casings for electrical measuring instruments.

One object of my invention is to provide a structure of the above indicated character that shall be compact, neat in appearance, rugged and durable in construction, economical to manufacture and effective in its operation.

Another object of my invention is to provide an instrument casing that shall be effectively permanently sealed around a window portion thereof.

A further object of my invention is to provide means for so mounting a glass window member in an instrument casing as to prevent injury to the window member.

In practicing my invention, I provide a casing structure having a yieldable window seat and a sealing member so related to the casing and so held in position as to effect a permanent seal around the window, to prevent injury to the window member, to economize in the manufacture of the casing and to render the same compact and neat in appearance.

Figure 1 of the accompanying drawings is a side sectional view of an instrument casing constructed in accordance with my invention, and

Fig. 2 is a view, similar to Fig. 1, of a modified form of my invention.

In the form shown in Fig. 1, my invention comprises, in general, a casing 1, a glass window member 2, a sealing member 3 and members 4 for holding the members 2 and 3 in position.

The casing 1 is preferably constructed of relatively thin sheet material, of tubular or cylindrical form, having an integral front end portion bent outwardly to provide a transverse perimetral shoulder 5 and bent inwardly, from the outer perimeter of the shoulder 5, to provide an inwardly projecting flexible flange 6.

The glass window member 2 is preferably

of the usual flat plate or discoidal form and is adapted to be inserted from the rear of the casing 1 for lateral positioning against the flange 6.

The sealing member 3, preferably constructed of insulating material, is constructed of tubular or cylindrical form to closely fit, and to have a relatively large bearing surface adjacent to, the inner surface of the casing 1. This construction permits the member 3 to telescope the casing, and to, therefore, be accurately centered or positioned with respect thereto.

The members 4, conforming on the lateral sides thereof to the adjacent surfaces of the casing 1, are provided with outwardly bent portions 7, at the outer ends thereof, for positioning against the shoulder 5 and, at the inner ends thereof, with inwardly projecting portions 8 for positioning behind the sealing member 3.

In assembling the device, the members 2, 3 and 4 are pressed inwardly, in assembled relation, from the rear of the casing to the position shown in the drawing. During this operation, by reason of the arrangement of the parts, the flange 6 is slightly flexed outwardly to permit the portions 7 to be properly fitted against the shoulder 5. The glass window member 2 is thus firmly held between the flexible flange 6 and the insulating sealing member 3 to effectively seal the casing and to prevent injury to the glass by temperature changes and other causes.

In Fig. 2, in which corresponding parts are designated by corresponding reference numerals, the construction is substantially the same as in the above described form, with the exception that members 9 are substituted for the members 4 to hold the members 2 and 3 in position. The members 9, preferably of metal and rectangular plate formation, are secured in flat-surface engagement with the inner surface of the casing 1 in any suitable manner, as by welding or soldering.

In assembling the device shown in Fig. 2, the members 2 and 3 are also pressed forwardly in the casing until sufficient pressure has been exerted against the flange 6 and the members 9 afterwards mounted in position.

In both forms of my invention, the de-

vice is extremely simple and compact in construction, economical to manufacture and effective in its operation.

While I have shown and described particular forms of my invention, changes may be effected therein without departing from the spirit and scope thereof, as set forth in the appended claims.

I claim as my invention:

- 10 1. In combination, a casing having a window opening and a flange or seat portion around the opening, a window-member seated behind said flange and held in position thereby, a perimetral member adapted for insertion in the casing from the rear of said window to hold said window member in position and means for positively interlocking said perimetral member in position in the casing.
  - 20 2. In combination, a tubular casing having a perimetral front-end flange, a window-member for insertion through the rear of the casing to position behind said flange and held in position thereby, a tubular member closely fitting the inner surface of the casing for insertion through the rear thereof to position against said window member and means for positively interlocking said tubular member in position in the casing.
  - 30 3. In combination, a tubular casing having a perimetral front-end flange, a window member for insertion through the rear of the casing to position behind said flange and held in position thereby, a tubular member closely fitting the inner surface of the casing for insertion through the rear thereof to position against said window member and means projecting inwardly from the inner surface of the casing behind said tubular member for holding the latter in position.
  - 40 4. In combination, a casing having a window opening and a flange around the opening, a window plate seated laterally behind said flange and held in position thereby, and a member of non-metallic sheet material engaging and extending normal to said plate, and means for holding said non-metallic member in positively interlocked relation to the casing to hold the plate in position.
  - 50 5. In combination, a relatively thin sheet-metal cylindrical casing having a flexible inwardly projecting perimetral front-end flange, a circular window plate disposed in the casing adjacent to said flange, a non-metallic cylinder closely fitting the casing adjacent to said plate and means for positively interlocking the cylinder in position in the casing.
  - 60 6. In combination, a relatively thin sheet-
- metal cylindrical casing having a flexible inwardly projecting perimetral front-end flange, a circular window plate disposed in the casing adjacent to said flange, a non-metallic cylinder closely fitting the casing adjacent to said plate and extending inwardly a certain distance therefrom and means projecting inwardly from the casing behind said non-metallic cylinder for holding the latter in position, the operative positioning of said means being permitted by pressing the non-metallic tube and the plate to flex said flange.
7. In combination, a casing having a transverse shoulder, a window-member, an inner sealing or seat member for the window member and a member between a portion of the casing and the window member having a portion engaging said shoulder and a portion behind said seat member.
8. In combination, a casing having a transverse shoulder, a window member, an inner sealing or seat member for the window member and a plurality of angularly spaced members each extending longitudinally in the casing between a portion of the latter and the window member having a transverse portion engaging said shoulder and a transverse portion behind said seat member.
9. In combination, a tubular casing having an outwardly extending transverse shoulder and an inwardly extending transverse flange, a window member seated laterally against said flange, a sealing or seat member behind said window member and a member between a portion of the casing and the window member having a portion engaging said shoulder and a portion for holding said seat member in position.
10. In combination, a sheet-material tubular casing having a front-end portion bent outwardly to provide a transverse perimetral shoulder and bent inwardly from the outer perimeter of said shoulder to provide a flexible perimetral flange, a window member seated laterally against said flange in the casing, a perimetral sealing member behind said window member and a member disposed between the sealing member and the inner surface of the casing having an outwardly projecting outer end portion for position over said shoulder and an inwardly projecting inner end portion for position behind said sealing member.
- In testimony whereof, I have hereunto subscribed my name this 11th day of January 1923.

PAUL MACGAHAN,
